(57) **CLAIM**

The ornamental design for a vehicle emergency escape tool, as shown and described.

DESCRIPTION

1.1 : Perspective

1.2 : Front

1.3 : Back

1.4 : Left

1.5 : Right

1.6 : Top

1.7 : Bottom

1.8 : an overall form of top view

1.9 : an overall form of back view

1.10 : an over all of bottom view

1.11 : reference view in an open position

1.12 : reference view in an open position

The present design is for a vehicle emergency escape tool which is used for emergence escape of a user (users) by cutting a safety belt and breaking glass, and which is used to accommodate spectacles or the like in a state that the vehicle emergency escape tool is combined with a vehicle sunshade at ordinary times; fig. **1.1** is a drawing expressing an overall form of the present design, fig. **1.2** is a drawing expressing a front surface portion of the present design, fig. **1.3** is a drawing expressing a back surface portion of the present design, fig. **1.4** is a drawing expressing a left side portion of the present design, fig. **1.5** is a drawing expressing a right side portion of the present design, fig. **1.6** is a drawing expressing a top portion of the present design, fig. **1.7** is a drawing expressing a bottom portion of the present design, fig. **1.8** is a drawing expressing an overall form of a top part of the present design, fig. **1.9** is a drawing expressing an overall form of a back part of the present design, fig. **1.10** is a drawing expressing an overall form of a bottom part of the present design, and figs. **1.11** and **1.12** are reference views, in an open position, of the present design.
